UNITED STATES PATENT OFFICE.

MATTHEW WIARD AND CHARLES C. PETTIT, OF PHILADELPHIA, PA.

DESIGN FOR HAY-RACKS.

Specification forming part of Design No. **11,250**, dated June 17, 1879; application filed April 21, 1879.
[Term of patent 3½ years.]

To all whom it may concern:

Be it known that we, MATTHEW WIARD and CHARLES COOPER PETTIT, both of Philadelphia, in the county of Philadelphia and State of Pennsylvania, have invented an Improved Design for Hay-Racks, of which the following is a specification.

Our invention relates to that class of stable-castings known as "hay-racks;" and consists in constructing the same of essentially three separate parts, which, when put in position and secured there, form one.

By raising or lowering the upper casting, the rods which form the middle part may be made loose or fast when in position. The lower part consists of a light open casting with diamond-shaped ornamentation in front and Prince Rupert drop openings on the bottom; and since the rods forming the middle part are not cast solid in the lower part, this portion can be used, if desired, as a sponge-basket.

The object of our invention is to construct a hay-rack of a suitable design, whereby cheapness, beauty, and strength are obtained, and to make the parts replaceable.

In hay-racks as usually constructed they are in one piece if casting be used, but are usually made almost exclusively of wrought-iron, riveted together or secured together by cast-iron hubs with drilled holes, which of necessity incurs considerable expense in the manufacture; and when cast-iron was used with wrought-iron, two parts were made solid, so that if one part should break the whole rack had to be thrown away. By constructing a hay-rack after our design we obviate all these difficulties.

Referring to the accompanying drawings, Figure 1 is an elevation of our newly-designed hay-rack. Fig. 2 is a cross-section of same. Fig. 3 is a plan showing segmental form of hay-rack.

A is the upper part, and is strengthened by

circumferential ribs *a*, *a'*, and *J*, which end in lugs *I I*, wherewith it is secured to the corner of the stall. Upon the rib *J* are cast hubs *H*, which are supplied with cored holes, into which rods or sections of gas-pipe *B B* fit loosely. These rods or pipe *B B* fit into cored holes in hubs *G G*, at the bottom, in lower segmental casting, *C*. This casting has two small ribs or beads, *c c'*, at the top, then diamond ornaments *D D* immediately under them, then another rib, and under it Prince Rupert drop openings *E E*. Upon the sides are lugs *F F F*, to secure it to the stall-wall.

The segmental shape of rack is shown in plan in Fig. 3, in which *X Z X* represent the corner of stall-walls. After the part *C* has been put in position and secured there, the rods or pipe *B B* are put in and the top *A* placed upon them and secured to the sides of the stall. If the top *A* is not pressed down tightly upon the rods or pipes *B B*, they may be revolved by the hand.

By making the castings *A* and *C* separately the hubs *H H* and *G G* are made perfect, which is not the case in other racks, and hence the rack as a whole becomes much stronger than the ordinary hay-racks, and at the same time much cheaper in construction. The bottom part, *C*, can be used as a sponge-basket, and when used as such it should have the hubs *G G* left off the casting. There is no expensive finishing on our improved design for racks. All holes are cored.

We claim—

In design, a hay-rack composed of castings *A* and *C* and removable rods or pipe *B B*, substantially as and for the purpose specified.

In testimony of which invention we hereunto set our hands.

MATTHEW WIARD,
CHARLES C. PETTIT.
